UNITED STATES PATENT OFFICE.

LAWRENCE C. COLLINS AND ARTHUR R. ELTOM, OF CRANFORD, NEW JERSEY.

TROLLEY-POLE.

No. 896,198.

Specification of Letters Patent.

Patented Aug. 18, 1908.

Application filed February 28, 1908. Serial No. 418,309.

To all whom it may concern:

Be it known that we, LAWRENCE C. COLLINS and ARTHUR R. ELTOM, citizens of the United States, residing at Cranford, in the county of Union, State of New Jersey, have invented certain new and useful Improvements in Trolley-Poles; and we do hereby declare the following to be a full, clear, and exact description of the invention, such as 10 will enable others skilled in the art to which it appertains to make and use the same.

The present invention has reference to improvements in trolley poles, and it resides, primarily, in the provision of an exceedingly 15 simple, inexpensive and efficient self-seating device of that nature comprising a pair of telescoping members, the inner member carrying the trolley wheel which is held normally against the trolley wire by the action 20 of the usual spring secured to the car roof.

More especially, the invention resides in the specific construction of the pole members; in the particular devices utilized for applying a yielding outward pressure upon 25 the inner pole member; in the particular manner in which such devices are connected with said members; and in the particular devices employed for retracting the inner member against the action of the first-mentioned 30 devices.

The invention will be readily understood from a consideration of the following detailed description, and its preferred embodiment is illustrated in the accompanying drawings, in 35 which corresponding parts or features, as the case may be, are designated by similar reference numerals in the several views.

Of the said drawings: Figure 1 is a fragmental side elevation of a car provided with 40 the improved trolley pole. Fig. 2 is a view of the upper end of the pole taken at right angles to Fig. 1. Fig. 3 is a longitudinal section through the pole. Fig. 4 is an enlarged detail view of the rocking lever. Fig. 5 is a 45 transverse section on the line 5—5 of Fig. 3.

Referring more particularly to the drawings, the trolley pole 1, whose lower end is fitted in the pivoted sleeve 2 mounted in the usual manner upon the car roof, is shown as 50 comprising an outer member 3 having a longitudinal socket 4 formed therein, and an inner member 5, slidable within said socket, the projecting end of the last-mentioned member having secured thereto the trolley- 55 wheel 6 which travels along the under side of the trolley-wire 7. The pole, as a whole,

is normally forced upwards toward the wire by the usual retractile coil-spring 9 which is likewise located upon the car roof and is connected at one end to the sleeve above referred to, the wheel being in this manner held yieldingly against the wire. 60

The outer member has formed therein a pair of diametrically-opposite slots 10 which communicate with the socket 4, the inner 65 member carrying a cross-pin 11 whose opposite ends project through said slots and through alining openings formed in a sliding collar 12 carried by the first-mentioned member, which latter is further provided with a 70 second collar 13 disposed below the collar 12. The collar 13 is held in position upon the pole-member 3 by a thumb screw or similar fastening device, and is thus stationary relative to the collar 12. Between said collars 75 is interposed an expandible coil-spring 14 secured at opposite ends thereto, the tension of said spring being exerted upon the sliding collar 12, which is thus forced away from the collar 13 projecting the member 5 outwardly 80 of the member 3. The tension of the coil-spring 14 is, however, considerably less than that of the spring 9; consequently, where the trolley-wheel is traveling along wires 85 strung at more than the usual distance from the ground, the pole will be raised into a more nearly vertical position, and the wheel-carrying member will be forced inwardly into the socket 4, the spring 14 yielding under the greater pressure of the spring 9. When, 90 however, the wheel is displaced from the wire from any cause, the tension of the spring 14 will at once move the wheel-carrying member outwardly.

In order to effect an automatic return of 95 the wheel to the wire in such instances, the pole is provided with a double lever 15. This element, as shown in Fig. 5, comprises a pair of similar arms 16 disposed upon opposite sides of the pole and provided with 100 centrally-located alining openings through which the ends of the cross-pin 11 project, displacement of said arms from the pin being prevented by inner and outer washers 17 and 18. The lower end of each arm 16 is 105 provided with an integral extension 19 which is set at an acute angle thereto and is provided with an arcuate slot 20, said extensions being disposed parallel with each other. The upper ends of said arms are bent 110 laterally towards each other, as indicated by the numeral 21, and then downwards par-

allel with each other, as at 22, the curved ends of the last-mentioned portions being connected together to form a U-shaped bracket in which a second trolley-wheel 23 is disposed, said wheel being mounted upon a journal pin 24 carried by the arms of said bracket *i. e.*, the bent portions 22, above referred to.

The stationary collar 13 is provided with a pair of diametrically-opposite laterally-projecting pins 25, upon each of which is rotatably mounted a flanged roller 26 whose reduced inner portion extends through the adjacent slot 20.

From the foregoing, it will be apparent that upon any accidental displacement of the wheel 6 from the trolley wire, the pole will be swung upwardly upon its pivot by the contraction of the spring 9, such movement carrying the wheel above the wire and bringing into contact with the latter, one or the other of the bent ends 21 of the lever arms, according as the wheel leaves the wire from one side or the other. At the same time, the inner member 5 will be projected outwardly of the member 1, under the action of the spring 14, which movement will correspondingly swing the lever 15 into a more nearly vertical position, the rollers 26 approaching the right-hand ends of the slots 20. The tension of the spring 9, however, is sufficiently great to more than counterbalance that of the spring 14, and therefore, when the bent end 21 of either lever arm is brought into contact with the wire, the lever 15 will be rocked upon its pivot, the wheel end of said lever being depressed and its slotted end raised. The extensions 19 in which said slots are formed are set at an acute angle to the lever arms, as above stated; by reason of such disposition, the rocking movement of the lever will therefore cause the rollers 26 to approach the left hand end of said slots, and since the distance between said slot ends and the cross pin 11 is less than that between the latter and the right hand ends of said slots, the sliding collar will be forced to move downwardly upon the pole member 3, thus retracting the member 5 and subsequently reengaging the wheel 6 with the wire. The ends 21 are bent downwards towards each other and, on this account, serve as guides to direct the wire towards the wheels 23 and 6, which are disposed in alinement with each other. It will thus be seen that the main trolley wheel will be automatically returned to reengagement with the wire in the event of displacement therefrom, thus completely dispensing with the use of guides beneath bridges and over railway crossings.

What is claimed is:—

1. A self-seating trolley pole, comprising in combination, inner and outer telescoping members; a trolley wheel carried by the in-

ner member; means connected with the outer member for normally raising the pole bodily, to engage said wheel with the trolley-wire; means for yieldingly projecting the inner member; and an automatically-operated lever connected with both of said members for retracting the inner member against the action of said last-mentioned means, when the wheel leaves the wire, to effect the reengagement of said wheel with the wire.

2. A self-seating trolley pole, comprising, in combination, inner and outer telescoping members, the outer member being provided with a longitudinal slot, and the inner member with a lateral pin projecting through said slot; a trolley-wheel secured to the inner member; means connected with the outer member for normally raising the pole bodily, to engage said wheel with the trolley-wire; means carried by the outer member and connected with said pin, for yieldingly projecting the inner member; and an automatically-operated lever connected with both of said members, for retracting the inner member against the action of said projecting means, when the wheel leaves the wire, to effect the reengagement of the wheel with the wire.

3. A self-seating trolley pole, comprising, in combination, inner and outer telescoping members, the outer member being provided with a pair of oppositely-disposed longitudinal slots, and the inner member with a cross-pin projecting at opposite ends through said slots; a trolley wheel secured to the inner member; means connected with the outer member for normally raising the pole bodily, to engage said wheel with the trolley-wire; means carried by the outer member and connected with the inner member, for yieldingly projecting the latter; and a lever for retracting the inner member against the action of said projecting means, when the wheel leaves the wire, to reengage the wheel with the wire, said lever comprising a pair of similar members disposed upon opposite sides of the outer member and having their adjacent ends connected together, each of said members being connected with said pin and with the outer member.

4. A self-seating trolley pole, comprising, in combination, inner and outer telescoping members; a trolley wheel carried by the inner member; means connected with the outer member for normally raising the pole bodily, to engage said wheel with the trolley-wire; a pair of spaced collars carried by the outer member, one of said collars being stationary and the other collar slidable, said sliding collar having a rigid connection with the inner member; a spring bearing at opposite ends against said collars, for yieldingly projecting the inner member; and a rocking lever pivoted to said sliding collar and connected with said stationary collar, for re-

tracting the inner member against the action of said spring, when the wheel leaves the wire, to reengage the wheel with the wire.

5. A self-seating trolley pole, comprising, in combination, inner and outer telescoping members, the outer member being provided with a pair of oppositely-disposed longitudinal slots, and the inner member with a cross-pin projecting at opposite ends through said slots; a trolley-wheel carried by the inner member; means connected with the outer member for normally raising the pole bodily, to engage said wheel with the trolley-wire; a fixed collar and a sliding collar carried by the outer member and arranged in spaced relation to each other, said sliding collar being secured to the ends of said pin; a spring interposed between said collars and bearing at opposite ends against the same, for yieldingly projecting the inner member; and an automatically-operated lever for retracting the inner member against the action of said spring when the wheel leaves the wire, to reengage the said wheel with the wire, said lever comprising a pair of similar members disposed upon opposite sides of said outer member and having their adjacent ends connected together, the members of said lever being pivoted centrally upon the ends of said pin and having their lower ends connected with said fixed collar.
6. A self-seating trolley pole, comprising, in combination, inner and outer telescoping members; a trolley wheel carried by the inner member; means connected with the outer member, for normally raising the pole bodily, to engage said wheel with the trolley-wire; a fixed collar and a sliding collar carried by the outer member and arranged in spaced relation to each other, said sliding collar having a rigid connection with said inner member; a spring interposed between said collars and bearing at opposite ends against the same, for yieldingly projecting the inner member; and an automatically-operated lever pivotally connected intermediate its ends with said sliding collar, and having its lower end slidably connected with said fixed collar, for retracting the inner member against the action of said spring, when the wheel leaves the wire to reengage said wheel with the wire.

7. A self-seating trolley pole, comprising, in combination, inner and outer telescoping members, a trolley wheel carried by the inner member; a fixed collar and a sliding collar carried by the outer member and arranged in spaced relation to each other, said sliding collar having a rigid connection with the inner member; a spring interposed between said collars and bearing at opposite ends against the same, for yieldingly projecting the inner member; a lever pivoted intermediate its ends to said sliding collar and provided at its lower end with a slotted angular extension; and a roller carried by said fixed collar and extending into the slot in said extension.

8. A self-seating trolley pole, comprising, in combination, inner and outer telescoping members; the outer member being provided with a pair of oppositely-disposed longitudinal slots, and the inner member with a cross-pin projecting at opposite ends through said slots; a trolley wheel carried by the inner member; means connected with the outer member for normally raising the pole bodily, to engage said wheel with the trolley-wire; a fixed collar and a sliding collar carried by the outer member and arranged in spaced relation to each other, said sliding collar being secured to the ends of said pin; a spring interposed between said collars and bearing at opposite ends against the same for yieldingly projecting the inner member; a lever for retracting the inner member against the action of said spring, said lever comprising a pair of similar arms disposed upon opposite sides of the outer member, the lower end of each arm being provided with an angular extension having an arcuate slot formed therein, the free ends of said extensions and the upper ends of said arms being connected together; a pair of oppositely-disposed lateral pins carried by said fixed collar; and a roller carried by each pin and extending into the slot in the adjacent extension.

In testimony whereof, we affix our signatures, in presence of two witnesses.
